UNITED STATES PATENT OFFICE.

JOSEPH THOMAS SCHIEFFELIN, OF LOUISVILLE, KENTUCKY.

DESIGN FOR A PUZZLE BOX OR CASE.

SPECIFICATION forming part of Design No. 29,400, dated September 20, 1898.

Application filed August 29, 1898. Serial No. 689,810. Term of patent 3½ years.

To all whom it may concern:

Be it known that I, JOSEPH THOMAS SCHIEFFELIN, a citizen of the United States, residing at Louisville, in the county of Jefferson and State of Kentucky, have invented and produced a new and original Design for a Puzzle Box or Case, of which the following is a specification, reference being had to the accompanying drawings, forming part thereof, in which—

Figure 1 is a plan view of my newly-designed puzzle box or case, and Fig. 2 a transverse section thereof.

As shown in the drawings, the leading or material feature of my design consists of a bottom A, comprising a board provided with a smooth upper surface, and on which is formed or secured four vertical side walls or flanges B, one of which is at a predetermined distance from the corresponding side or edge of the bottom board A, forming a space b outside of the inclosure formed by the vertical walls or flanges B.

In the vertical wall or flange B adjacent to the space b is formed a passage b², which is inclosed on the outer side of said wall by a chamber b³, formed by three vertical walls b⁴, two of which connect with the adjacent wall or flange B.

Within the space formed by the walls B is arranged a continuous wall or flange D, which begins at d near the center of the bottom board A, and by means of which a central space E is formed, in which is placed a loop-shaped wall or flange G, which begins at g and connects with the wall D at g², and where-

by a smaller oblong chamber g³ is formed, which communicates with the space E at g⁴. The wall or flange D follows the general form of the board A, but is folded backwardly upon itself at H and H² and terminates in connection with one of the side walls B at h, and by means of this arrangement of the wall or flange D a continuous passage K is formed from the chamber b³ at one side of the device to the smaller oblong chamber g³ at the middle thereof.

The folds or bends in the wall or flange D are in radial line with the corners formed by the side walls or flanges B, and the continuous passage K is provided at said corners or a portion thereof with brackets L, and a similar bracket L is placed adjacent to each of the reverse bends H and H² in the wall D and on the inner side of said bends, and the continuous wall D and the continuous space K formed thereby are provided with a transparent cover M.

Having fully described my invention, I claim as new and desire to secure by Letters Patent—

The design for a puzzle box or case herein shown and described.

In testimony that I claim the foregoing as my invention I have signed my name, in presence of the subscribing witnesses, this 24th day of August, 1898.

JOSEPH THOMAS SCHIEFFELIN.
